(57) **CLAIM**

The ornamental design for a lock for an adjustable locking leg assembly, as shown and described.

DESCRIPTION

FIG. 1 is a perspective view showing a first side of a lock for an adjustable locking leg assembly.

FIG. 2 is a perspective view showing a second side of the lock of FIG. 1.

FIG. 3 is a front view of the lock of FIG. 1.

FIG. 4 is a rear view of the lock of FIG. 1.

FIG. 5 is a top view of the lock of FIG. 1.

FIG. 6 is a bottom view of the lock of FIG. 1.

FIG. 7 is a left side view of the lock of FIG. 1; and, FIG. 8 is a right side view of the lock of FIG. 1.

The broken lines are for the purpose of illustrating portions of the article that form no part of the claim.

1 Claim, 7 Drawing Sheets
